GAME BOARD

James Hubert Guthrie, 35 Willis Lane,
St. Albans, W. Va. 25177

Filed Apr. 3, 1970, Ser. No. 22,237

Term of patent 14 years

Int. Cl. D21—01

U.S. Cl. D34—5

The figure is a plan view of a game board, showing my new design. The game board is of conventional thickness.

I claim:

The ornamental design for a game board, substantially as shown and described.
